ABSTRACT

A new and distinct cultivar of *Salvia* plant named 'Pink Delight', characterized by its upright and relatively compact plant habit; freely basal branching habit; dense and bushy plant form; freely flowering habit; and light violet purple-colored flowers.

1 Drawing Sheet

1

Botanical classification/cultivar designation: *Salvia hybrida* cultivar Pink Delight.

BACKGROUND OF THE INVENTION

The present Invention relates to a new and distinct cultivar of *Salvia* plant, botanically known as *Salvia hybrida*, and hereinafter referred to by the name 'Pink Delight'.

The new *Salvia* is a product of a planned breeding program conducted by the Inventor in Hummelo, The Netherlands. The objective of the breeding program was to create new compact *Salvia* cultivars with numerous flowers with attractive coloration.

The new *Salvia* originated from a self-pollination made by the Inventor during the summer of 1999 of a proprietary selection, not patented, from the cross-pollination of the *Salvia hybrida* cultivar Amethyst, not patented, and the *Salvia hybrida* cultivar Tanzerin, not patented. The new *Salvia* was discovered and selected by the Inventor during the spring of 2000 as a single flowering plant within the progeny of the stated self-pollination grown in a controlled environment in Hummelo, The Netherlands.

Asexual reproduction of the new cultivar by cuttings and divisions taken at Hummelo, The Netherlands, since the summer of 2000, has shown that the unique features of this new *Salvia* are stable and reproduced true to type in successive generations.

SUMMARY OF THE INVENTION

Plants of the cultivar Pink Delight have not been observed under all possible environmental conditions. The phenotype may vary somewhat with variations in environment such as temperature and light intensity without, however, any variance in genotype.

The following traits have been repeatedly observed and are determined to be the unique characteristics of 'Pink Delight'. These characteristics in combination distinguish 'Pink Delight' as a new and distinct *Salvia* cultivar:

1. Upright and relatively compact plant habit.
2. Freely basal branching, dense and bushy plant form.
3. Freely flowering habit.
4. Light violet purple-colored flowers.

2

Plants of the new *Salvia* are more compact than plants of the parent selection. Compared to plants of the *Salvia* cultivar Eveline, disclosed in U.S. Plant patent application Ser. No. 10/437,938 filed concurrently, plants of the new *Salvia* are more compact, broader, have shorter internodes, and differ in flower coloration.

BRIEF DESCRIPTION OF THE PHOTOGRAPH

10 The accompanying colored photograph illustrates the overall appearance of the new cultivar, showing the colors as true as it is reasonably possible to obtain in colored reproductions of this type. Colors in the photograph may differ slightly from the color values cited in the detailed botanical description which accurately describe the actual colors of the new *Salvia*. The photograph comprises a side perspective view of a typical flowering plant of 'Pink Delight' grown in a outdoor nursery.

DETAILED BOTANICAL DESCRIPTION

20 Plants shown in the aforementioned photograph and used in the following description were grown under conditions which closely approximate commercial production conditions during the late spring in an outdoor nursery in 25 Lisserbroek, The Netherlands. During the production of the plants, day temperatures ranged from 14 to 25° C. and night temperatures ranged from 4 to 16° C. Plants in the photograph and used for the description were about one year old when the photograph and description were taken. In the 30 following description, color references are made to The Royal Horticultural Society Colour Chart, 2001 Edition, except where general terms of ordinary dictionary significance are used.

35 Botanical classification: *Salvia hybrida* cultivar Pink Delight.

Parentage: Self-pollination of a proprietary selection, not patented, of the cross pollination of the *Salvia hybrida* cultivars Amethyst, not patented, and Tanzerin, not patented.

40 Propagation:

Type.—By cuttings.

Time to produce a rooted young plant.—About 60 days at 16 to 22° C.

Root description.—Thick.

Plant description:

Form.—Perennial. Upright and relatively compact plant habit; broad inverted triangle. Freely basal branching with about 18 flowering stems per plant; dense and bushy plant habit; moderately vigorous growth habit. Numerous flowers arranged in verticillasters on crowded spikes.

Plant height.—About 53 cm.

Plant width.—About 60 cm.

Flowering stem description.—Length: About 53 cm. Diameter: About 5 mm. Internode length: About 12 cm. Strength: Strong. Texture: Densely pubescence. Color: 143A.

Foliage description.—Arrangement: Opposite, simple. Length: About 10.5 cm. Width: About 6 mm. Shape: Ovate, elongated. Apex: Acute. Base: Cordate. Margin: Crenate. Texture, upper and lower surfaces: Fine pubescence; rugose. Venation pattern: Pinnate. Fragrance: When rubbed, sage-like. Color: Developing foliage, upper surface: 137A. Developing foliage, lower surface: 137C. Fully expanded foliage, upper surface: 139A. Fully expanded foliage, lower surface: 137B. Venation, upper surface: 144C. Venation, lower surface: 144B. Petiole length: About 1.5 cm. Petiole diameter: About 2.5 mm. Petiole color: 144B.

Flower description:

Flower arrangement and shape.—Single labiate flowers in verticillasters on spikes; flowers face outwardly. Freely flowering, flowers in whorls of six; about 90 flowers per spike.

Natural flowering season.—Continuous from mid-May into July in The Netherlands.

Flower longevity on the plant.—Individual flowers last about five days on the plant. Flowers not persistent.

Flower buds.—Length: About 9 mm. Diameter: About 5 mm. Shape: Ovoid. Color: 71A.

Inflorescence size.—Length: About 22 cm. Diameter: About 4.7 cm.

Flowers.—Diameter: About 1.6 cm by 8 mm. Depth (height): About 2.4 cm.

Petals.—Arrangement: Labiate; one upper lip and one lower lip with three lobes; lips fused at the base. Length: Upper petal: About 2 cm. Lower petal: About 1.7 cm. Width: Upper petal: About 1 mm. Lower petal: About 7 mm. Shape: Upper petal: Broadly elliptic. Lower petal: Spatulate. Apex:

Upper petal: Emarginate. Lower petal: Broadly emarginate. Margin, upper and lower petals: Entire. Texture, upper and lower petals: Pubescent. Color: Upper petal: When opening and fully opened, upper surface: 75C. When opening and fully opened, lower surface: 75A. Lower petal: When opening and fully opened, upper surface: N80A to N81B. When opening and fully opened, lower surface: 77B.

Sepals.—Arrangement: Five sepals fused into a tube. Length: About 9 mm. Width: About 2 mm. Shape: Elliptic. Apex: Acute. Margin: Entire. Texture, upper and lower surfaces: Pubescent. Color: When opening, upper surface: 146A. When opening, lower surface: 187A. Fully opened, upper surface: 143C with longitudinal stripes, 143A. Fully opened, lower surface: 138A.

Flower bracts.—Quantity per verticillaster: Two. Length: About 7 mm. Width: About 5 mm. Shape: Deltoid. Apex: Apiculate. Texture, upper and lower surfaces: Pubescent. Color, upper and lower surfaces: 144A to 144B.

Peduncles.—Strength: Strong. Length: About 53 cm. Diameter: About 2.5 mm. Aspect: Mostly upright. Color: 143A; towards the apex, N187A.

Pedicels.—Strength: Strong. Length: About 2 mm. Diameter: About 0.5 mm. Aspect: About 35° from vertical. Color: 138A.

Reproductive organs.—Stamens: Quantity per flower: Two. Anther shape: Narrowly elliptic. Anther length: About 3 mm. Anther color: N187A. Filament length: About 1.2 cm. Filament color: 76C to 76D. Pollen amount: Abundant. Pollen color: 6A. Pistils: Quantity per flower: One. Pistil length: About 2.4 cm. Stigma shape: Two-parted, cleft. Stigma color: 77A. Style length: About 2.1 cm. Style color: 155C. Ovary color: N144A.

Seed/fruit.—Seed and fruit production has not been observed.

Disease/pest resistance: Plants of the new *Salvia* have not been noted to be resistant to pathogens and pests common to *Salvia*.

Weather tolerance: Plants of the new *Salvia* have exhibited good tolerance to rain and wind and have been observed to tolerate temperatures from -25 to 35° C.

It is claimed:

1. A new and distinct cultivar of *Salvia* plant named 'Pink Delight', as illustrated and described.
